UNITED STATES PATENT OFFICE.

GEORGE L. CHAMBERLAIN, OF CHICAGO, ILLINOIS.

ELECTRICAL CONNECTION FOR TRANSFORMERS AND THE LIKE.

Application filed July 21, 1922. Serial No. 576,564.

To all whom it may concern:

Be it known that I, GEORGE L. CHAMBERLAIN, a citizen of the United States, and a resident of the city of Chicago, county of Cook, and State of Illinois, have invented certain new and useful Improvements in Electrical Connections for Transformers and the like, of which the following is a specification.

10 My invention relates to improvements in electrical connections for transformers and the like, and has for its object the provision of an improved electrical connection of this character which is of simple construction, 15 efficient in operation, and capable of ready shifting or adjustment to vary the output of the transformer.

Other objects will appear hereinafter.

The invention consists in the combinations 20 and arrangements of parts hereinafter described and claimed.

The invention will be best understood by reference to the accompanying drawings forming a part of this specification, and in 25 which,

Fig. 1 is a longitudinal section of a transformer equipped with a connection embodying the invention;

30 Fig. 2 is an enlarged section taken on line 2—2 of Fig. 1;

Fig. 3, an enlarged section taken on line 3—3 of Fig. 1; and

Fig. 4, a section taken on line 4—4 of Fig. 2.

35 The preferred form of construction as illustrated in the drawings comprises a transformer 5 of any usual or desired construction and enclosed in a metal casing 6 and supplied with current through the usual

40 primary leads 7 as indicated. The transformer 5 is also provided with three wires or leads 8 leading to the secondary winding thereof for varying the output of the transformer in the usual way. Leads 8 are con-

45 nected with three socket members 9 em- bedded in a base 10 of insulating material located at the inner end of a metallic tube 11 leading into the casing 6 as shown. A tube of insulating material 12 is arranged

50 within the tube 11 and provided at one side with a longitudinal slot 13 as shown. A removable head 14 is arranged to fit snugly within the tube 12, said head 14 being made of insulating material and in two separable

55 parts secured together by means of a screw 15. The head 14 is provided with a lateral

projection 16 to fit the groove 13 and whereby the association of the head 14 with the base 10 is compelled to be always in the same relation. The head carries two combined 60 socket and plug members loosely inserted in openings 17 in said head as indicated. The separable parts of the head 14 are each provided with three of the openings 17 grouped 65 symmetrically about the central binding 65 screw 15 and registering with each other. The combined socket and plug members, of which two are provided, fit snugly through two of the openings in the lower part 14 and are provided at their upper ends with heads 70 fitting corresponding recesses in the upper member 14. By this arrangement the combined socket and plug members may be readily arranged in any two of the openings 17. Each of these combined socket and plug 75 members is provided at its upper end with a socket 18 and at its lower end with a split plug 19, the openings 17 being arranged to register with the sockets 9 and whereby the plugs 19 will be caused to enter said sockets 80 when the head is inserted in the tube. Two secondary leads 20 are connected with the sockets 18 whereby said leads will be connected with the secondary winding of the transformer as will be readily understood. 85 By this arrangement it will be observed that one of the secondary leads may be readily shifted to connect with another of the sockets 9 thus affording the output of the transformer. One of the leads 8 is connected 90 with one end of the secondary winding of a transformer and the other leads 8 are connected at different portions thereof, so that the shifting of one of the members 18—19 will so change the connection with the trans- 95 former as to vary the output thereof, as will be readily understood by those skilled in this art.

The secondary leads 20 are enclosed in the usual lead pipe 21 connected with the tube 100 11 by means of a detachable union 22 whereby the secondary leads will be readily removed for adjustment for output and the joint readily sealed when the adjustment 105 has been made.

By this arrangement a simple and effective means is provided for varying the output of the transformer which may be readily adjusted by persons of comparatively little skill or knowledge in the art.

110 While I have illustrated and described the preferred form of construction for car-

rying my invention into effect, this is capable of variation and modification without departing from the spirit of the invention. I, therefore, do not wish to be limited to the 5 precise details of construction set forth, but desire to avail myself of such variations and modifications as come within the scope of the appended claims.

Having described my invention, what I 10 claim as new, and desire to secure by Letters Patent, is:

1. An electrical connection comprising one member having three slip connections thereon; a cooperating member having three 15 mountings thereon registering with the connections on said other member; two slip connections in said mountings and cooperating with the slip connections on said other member; means facilitating the shifting of one 20 of said slip connections from one of said mountings into the said unoccupied mounting; and means compelling association of said members always in the relation, substantially as described.
- 25 2. An electrical connection comprising one block of insulating material having three permanent slip sockets thereon; a co-operating block of insulating material having three mountings thereon registering 30 with said sockets; two plugs arranged in two of said mountings; means facilitating the ready shifting of one of said plugs from one of said mountings into the said unoccupied mounting; and means compelling association of said members always in the same 35 relation, substantially as described.
3. An electrical connector plug comprising two separable parts having three registering openings extending therethrough; 40 two combined socket and plug members extending through one of said parts and pro-

jecting therefrom, the projecting ends constituting plugs and there being sockets in the inner ends thereof; stop heads on the inner ends of said combined socket and plug members; a positioning projection projecting laterally from said connection; and readily detachable means for securing the parts of said connection together, substantially as described.

4. The combination of a casing, of a tube leading into said casing; a base at the inner end of said tube; three electric sockets mounted in said base; electrical connections leading from said sockets into said casing; a movable head fitting said tube; means compelling insertion of said head always in the same position; two plugs carried by said head and arranged to fit two of said sockets, one of said plugs being arranged to be readily adjusted to engage different of said sockets; and lead wires connected with said plugs, substantially as described.

5. The combination with a metallic casing, of a metallic tube leading into said casing; a base of insulating material at the inner end of said tube; three metallic electric sockets mounted in said base; a removable head of insulating material fitting into said tube; a lining for said tube of insulating material, there being a longitudinal slot in said insulating lining; a projection on said head engaging said slot; and two plugs carried by said head and adapted to engage two of said sockets, one of said plugs being arranged to be readily adjusted to engage different of said sockets, substantially as described.

In testimony whereof I have signed my name to this specification.

GEORGE L. CHAMBERLAIN.
